AMUSEMENT APPARATUS

John F. Courtney, Florence, S. C., assignor, by direct and mesne assignments, to Velare & Courtney, Inc., a corporation of Illinois

Application June 10, 1939, Serial No. 278,536

6 Claims. (Cl. 272—38)

My invention relates to amusement apparatus of the Ferris wheel type.

An important object of the invention is to provide apparatus of the above mentioned character, which will impart a plurality of separate movements to the passenger cars or seats, thus increasing the thrill.

A further object of the invention is to provide apparatus of the above mentioned character which will elevate the passenger to a high point, during the ride and return the passenger to the lowered loading position, while rotating the passenger about another point.

A further object of the invention is to provide apparatus of the above mentioned character which will produce a horizontal rotation, a vertical rotation, and a second vertical rotation with respect to the first named vertical rotation.

A further object of the invention is to provide means whereby the individual wheels may be turned independently, and stopped independently, for the purpose of loading or unloading.

A further object of the invention is to provide apparatus of the above mentioned character, formed in units which may be readily separable so that the same may be quickly and easily disassembled and assembled.

Further objects and advantages of the invention will be apparent during the course of the following description.

In the accompanying drawings forming a part of this application and in which like numerals are employed to designate like parts throughout the same,

Figure 1 is a perspective view of apparatus embodying my invention, showing the rotary support beam horizontal,

Figure 2 is a side elevation of the same,

Figure 2a is a perspective view of one of the drive pulleys and associated elements,

Figure 3 is an edge elevation of the apparatus, showing the support beam vertical,

Figure 4 is a vertical transverse section taken on line 4—4 of Figure 2,

Figure 5 is a side elevation of the apparatus showing the support beam vertical,

Figure 6 is a detailed section taken on line 6—6 of Figure 3,

Figure 7 is a detailed section taken on line 7—7 of Figure 3,

Figure 8 is an enlarged side elevation of the support beam and associated elements, parts broken away,

Figure 9 is a transverse section taken on line 9—9 of Figure 8, and

Figure 10 is a transverse section taken on line 10—10 of Figure 9.

The apparatus comprises a horizontally rotating turn-table 10, mounted upon wheels 11, traveling upon a circular track 12. The upper surface of the turn-table is near the level of the ground so that the riders may conveniently step upon the turn-table. One wheel 11, Figure 6, is provided with an internal annular gear 13, driven by a gear 14, rigidly secured to a shaft 15, driven by a motor 16. This motor is mounted upon the turn-table 10, as shown. Any suitable form of circuit and switch may be employed for the motor. Any suitable form of brake device may be employed to stop the turn-table. I may employ an electric brake, or the turn-table may be stopped by reversing the motor.

Rigidly mounted upon the turn-table 10 is a tower 17, comprising a pair of spaced vertical beams 18, attached at their lower ends to the turn-table and securely braced by diagonal rods 19 or the like. The tower rotates horizontally as a unit with the turn-table. Secured to the upper ends of the vertical beams 18 are bearings 20, receiving a horizontal rotatable shaft 21.

Rigidly mounted upon the shaft 21 to rotate therewith is a rotary supporter beam 22. The beam 22 comprises a pair of beam-sections 23, spaced as shown. The shaft 21 is equidistantly spaced from the ends of the beam-sections.

Rotatably mounted in the opposite ends of the beam-sections 23 are horizontal transverse shafts 24, upon which large wheels 25 are rigidly mounted. Each large wheel is provided with a plurality of passenger carrying elements 26, in the form of seats or cars. These passenger carrying elements are pivoted to the wheel adjacent to its periphery so that the passenger supporting elements remain vertical while they bodily rotate with the wheel. The wheels extend radially beyond the supporting beam 22 whereby the passenger is elevated to a very high point, during the operation of the apparatus. The arrangement is such that all of the passenger supporting elements on each large wheel may be entirely clear of the arm at one time. Further, the portion of each wheel extending beyond the carrying arms travels at a much higher speed with respect to the axis of rotation of the carrying arms than the portion of each wheel within the carrying arms.

The rotary beam 22 has an annular internal gear 27 rigidly attached to the same adjacent to the shaft 21. The gear 27 surrounds the shaft 21 and is concentric with respect to the shaft.

The annular gear is driven by a gear 28, in turn driven by a motor 29, rigidly mounted upon the beam 18, near the upper end thereof. The control switch for the motor is arranged upon the ground suitably near the platform.

Rigidly secured to the opposite end of the shaft 21 with respect to the annular gear 27 is a brake drum 29', engaged by a brake band 30'. Figures 9 and 10. One end of this brake band 30' is secured to the beam 18, and its opposite end is secured to a bell-crank lever 31', pivoted upon the beam 18. This bell-crank lever is connected with a cable 32', extending downwardly to engage with a pulley 33', and connected with a hand lever 34'. It is thus seen that when the motor 29 is stopped, the brakes may be applied to stop the rotation of the support beam, so that either wheel 25 may be stopped at a position, suitable for loading or unloading passengers.

The wheels 25 are separately rotated and separately braked. Each wheel 25 is rotated by a cable 30, engaging within forks 31, secured to the side of the wheel. The forks 31 are disposed near and inwardly of the periphery of the wheel. The cables 30 pass about pulleys 32 and also about slack take-up pulleys 33. Each pulley 32 is mounted upon a transverse shaft 34, suitably mounted upon the rotary beam 22, while the pulley 33 is mounted upon a shaft 35, suitably mounted within a guide 35, rigidly mounted upon the beam-section 23. The shaft 35 is moved in one direction by a spring 36', to automatically take up the slack in the cable 30, and to yield, to pay out the slack, when desired. The shaft 34 is driven by a motor 36, through suitable speed reduction gearing 37'. The motors 36 have separate circuits and the switches for these motors are arranged at the ground suitably near the turn-table. The motors are, of course, mounted upon the rotary beam 22. By having separate 40 motors, the wheels 25 are separately rotated and their speed of rotation may be varied with relation to each other, while one wheel may be rotating while the other wheel is stopped.

The shaft 24 of each wheel 25 is equipped with a brake device 37. This brake device embodies a drum 37' which is rigidly mounted upon the shaft 24, see Figures 4 and 7. This brake drum is engaged by a brake band 38', mounted within the stationary housing 39', rigidly attached to the beam-section 23. The brake band is connected with a pivoted lever 40' which operates the same, and this pivoted lever is connected with a rod 38. There are two of these rods and they extend inwardly and longitudinally of the beam-sections 23. When the rod is shifted inwardly and longitudinally of the rotary beam 22 the brake is applied to stop the shaft 24. The rod 38 is mounted upon the beam-section 23 to reciprocate with relation thereto and is held within guides 41', mounted upon the beam-section 23. At its inner end, the rod 38 is provided with a laterally extending shoulder 39, adapted for co-action with a lever 40, pivoted to the beam 18, as shown at 41. The lever 40 is pivotally connected at its outer end, at 42, with a rod 43. This rod operates through suitable guides 44. The rod is moved upwardly by a spring 45, and is moved downwardly by a lever 46, which may be a treadle. The lever 40 serves to apply the brakes to the shafts 24 of both wheels, separately, but before the brakes can be applied, the rotary beam 22 must be in the vertical position, so that the shoulder 39 of the brake device of the wheel 25 in the lowered position, will be po-

sitioned above and in alignment with the lever 40.

The numeral 47 designates loading steps arranged upon the turn-table 10.

- 5 The operation of the apparatus is as follows: The turn-table 10 is rotated horizontally and may be rotated continuously at a slow speed, although the same may be stopped to take on or let off passengers, if desired. The tower rotates 10 horizontally with the turn-table and the wheels 25 accordingly rotate bodily horizontally with the tower. The beam 22 rotates vertically about the axis of the shaft 21, as this shaft is driven by the motor 29. While the beam is rotating vertically, it carries the wheels 25 with it which travel in a vertical circular path. While traveling in the vertical circular path these wheels 25 are separately rotated in a vertical plane about the shafts 24, by the motors 36. The wheels 25 15 are separately rotated and may be rotated at different speeds. The rotation of the wheels is independent of the rotation of the rotary beam. To load or unload passengers, the rotary beam 22 is stopped in the vertical position. The motor driving the lowered wheel 25 may have the current cut off therefrom and the lowered wheel will then continue to rotate by inertia until stopped by its brake. At this time, the shoulder 39 will be above and in alignment with the lever 40. The lever 46 is now depressed and the rod 43 drawn downwardly. The inner end of the lever 40 moves upwardly and engages the shoulder 39. The shoulder is drawn inwardly which draws the rod 38 inwardly, actuating the brake 37 to stop the shaft 24. The brake cannot be applied until the beam 22 is in a substantially vertical position.

It is to be understood that the form of my invention herewith shown and described is to be taken as a preferred example of the same and that various changes in the shape, size, and arrangement of parts may be resorted to without departing from the spirit of my invention or the scope of the subjoined claims.

45 Having thus described my invention, what I claim is:

1. In an amusement apparatus, a tower, a vertically rotating supporting element mounted upon the upper portion of the tower, wheels mounted upon the ends of the supporting element and projecting radially beyond the same, said wheels being rotatable in the plane of rotation of the supporting element, passenger carrying elements mounted upon each wheel, separate means to rotate each wheel, a separate brake device for each wheel mounted upon the supporting element, each brake device having an operating part, and operating means mounted upon the tower and common to all operating parts and adapted to move each operating part separately when such operating part is moved into a proper position with relation to the operating means.

65 2. In an amusement apparatus, a tower, a vertically rotating supporting element mounted upon the tower, wheels mounted upon the supporting element and rotatable in the plane of rotation of the supporting element, passenger supporting elements mounted upon each wheel, separate brake devices for the wheels and having operating parts mounted upon the supporting element, a movable element mounted upon the tower and adapted to actuate each operating part when such operating part is moved into close

relation to the movable element, and means to move the movable element.

3. In an amusement apparatus, a tower, a vertically rotating supporting element mounted upon the tower and having arms, wheels mounted upon the arms near the outer ends and rotating in the plane of rotation of the supporting element, passenger carrying elements mounted upon the wheels, separate brake devices for the wheels, elements to operate the brake devices and extending inwardly of the arms and mounted thereon, said elements having engaging parts, a lever pivoted upon the tower and arranged upon one side of each engaging part when the engaging part is shifted to a position near the lever, and means to move the lever so that it will contact with the engaging part and move the same.

4. In an amusement apparatus, a tower, a supporting beam pivotally mounted between its ends upon the tower, wheels pivotally mounted upon the ends of the supporting beam, passenger carrying elements mounted upon each wheel, separate means to turn each wheel, separate brake devices for the wheels including members extending radially inwardly of the supporting beam, said members having lateral extensions, the lateral extensions being spaced from each other, a lever pivoted to the tower and having one end arranged upon one side of each lateral extension when the lateral extension is shifted to a position in proximity to the lever, and means to move the lever to cause its end to contact with the lateral extension and move the lateral extension.

5. In an amusement apparatus, a tower, a supporting beam mounted upon the tower to rotate vertically, means mounted upon the tower to rotate the supporting beam, wheels mounted upon the ends of the supporting beam to rotate vertically, passenger supporting elements mounted upon each wheel, a separate device mounted upon

the supporting beam to rotate each wheel, a separate brake device for each wheel, and means common to all brake devices to operate the brake device of each wheel separately to stop the wheel only when the beam is substantially vertical.

6. In an amusement apparatus, a tower, a beam rotatably mounted upon the upper portion of the tower and having only two radially extending arms which are oppositely arranged and of approximately the same length, means to rotate the beam, large wheels rotatably mounted upon the outer end portions of the arms and having diameters considerably greater than the length of each arm, each wheel extending radially beyond the outer end of its arm for a distance equal to at least the major portion of the length of such arm, the portion of each wheel extending beyond the carrying arms traveling at a much higher speed with respect to the axis of rotation of the carrying arms than the portion of each wheel within the carrying arms, passenger supporting elements pivotally mounted upon each large wheel adjacent to its periphery, each large wheel having its inner portion inwardly of the rotatable mounting of the wheel upon the arm extending laterally beyond the opposite sides of the arm, the arrangement being such that all of the passenger supporting elements on each large wheel may be entirely clear of the arm at one time, means to rotate each large wheel with respect to its arm, a separate brake device for each wheel mounted upon the arm, each brake device having an operating part, and operating means mounted upon the tower and common to all operating parts and adapted to move each operating part separately when such operating part is moved into a proper position with relation to the operating means.

JOHN F. COURTNEY.
